W. H. SARGENT.

WASHING MACHINE.

APPLICATION FILED APR. 4, 1919.

1,350,115.

Patented Aug. 17, 1920.

Inventor:

William H. Sargent

by Bruce S. Feinberg

His ATTY.

UNITED STATES PATENT OFFICE.

WILLIAM H. SARGENT, OF ST. LOUIS, MISSOURI, ASSIGNOR TO WAYNE MANUFACTURING COMPANY, OF ST. LOUIS, MISSOURI, A CORPORATION OF MISSOURI.

WASHING-MACHINE.

1,350,115.

Specification of Letters Patent. Patented Aug. 17, 1920.

Application filed April 4, 1919. Serial No. 287,564.

To all whom it may concern:

Be it known that I, WILLIAM H. SARGENT, a citizen of the United States, residing in the city of St. Louis and State of Missouri, have invented new and useful Improvements in Washing - Machines, of which the following is a specification.

This invention relates to apparatus such as domestic washing machines which may be used in the household for washing clothes. The invention is particularly applicable to the type of washing machines that are driven by a small motor. The general object of the invention is to provide improved means for receiving the oscillating movement at the receptacle or tub. According to this feature of the invention, I provide means for distributing the strains on the side of the tub, that are incident to the rocking or oscillating movement. When applied to a washing machine having a clothes wringer as an accessory, I provide means for driving the wringer or oscillating the tub independently of each other. Another object of the invention is to provide means whereby the washing machine can be readily converted into a churn.

Further objects of the invention will appear hereinafter.

The invention consists in the general combination of parts and in the features of said parts hereinafter described, all of which contribute to produce an efficient washing machine.

A preferred embodiment of my invention will be particularly described in the following specification, while the broad scope of my invention will be pointed out in the appended claims.

In the drawing,

Figure 1 is a side elevation of the apparatus, certain parts being broken away;

Fig. 2 is an end elevation of the machine shown in Fig. 1, certain parts of the machine being broken away;

Fig. 3 is an end elevation, partially broken away, illustrating the means I employ for converting the washing machine into a churn.

Referring more particularly to the parts, 1 represents the frame of the machine which may be of any suitable construction, but preferably having two elevated side bars 2 between which the receptacle or tub

3 is supported. This tub may be of any

suitable form, but, as illustrated, is of elongated box form, presenting flat vertical sides 4, and a bottom 5 having curved portions 6 which connect the bottom with the end walls of the tub.

The receptacle is provided with a removable cover 7 which is received in a neck 8 extending up from an opening 9 in the upper wall of the tub. The inner face of the bottom and end walls of the tub are provided with a corrugated or washboard lining 10 adapted to exert a washing action upon the clothes when the receptacle or tub is oscillated.

Such a receptacle or tub is usually oscillated by means of a connecting rod, and as the water within the tub may acquire considerable momentum in the reciprocating movement, the point of connection of the connecting rod to the tub is subjected to considerable local strain. For this reason, I provide means for distributing the strain at this point.

In order to provide for distributing the strain arising from transmitting the oscillating movement to the receptacle, I prefer to provide a bracket which may be of substantial triangular form, see Fig. 1. I provide such a bracket 11 on one side, and a similar bracket 12 on the opposite side. The sides 4 of such a tub are usually formed of a plate of sheet metal, and this plate presents a projection or flange 13 running along the lower edge of the tub, adjacent the bottom 5, and it also presents upper projections or flanges 14 disposed on opposite sides of the vertical middle axis of the side of the tub, for example toward each end, and preferably on the elevated corners of the ends of the tub. The flanges 14 may be continuations of the flange 13.

The brackets 11 and 12 are provided with sockets 15 which receive the bottom flanges or projections 13, and beyond these sockets 15, each bracket is formed with a shoe 16, which projects under the bottom.

Securing means is provided for clamping the brackets 11 and 12 on the sides of the tub, and this securing means includes four saddles 17. These saddles are simply in the form of curved plates which seat on the projections or flanges 14 at the upper corners of the sides of the tub. To this end, each saddle is formed with a socket 18 which receives the projection or flange 14 at this

point. Furthermore each of these saddles 17 is connected by a tension rod 19 with its corresponding bracket 11 or 12. This may be accomplished by means of an integral 5 lug 20 on the side of the bracket, through which the end of the stem or rod 19 passes, and on this lug a nut 21 seats. It will be evident that in order to make this connection secure, it is necessary that the 10 flange 14 shall be disposed at an elevated point, and located on opposite sides of the vertical axis of the side of the tub, so that when the nuts 21 are screwed up, tension will be developed in each rod, which will 15 result in pulling the shoes 16 of the brackets tightly up against the bottom flange.

In order to support the tub on the frame so that it will oscillate, I prefer to provide the upper ends of the side brackets with 20 trunnions 22 respectively, and these trunnions are received in sockets 23 formed in the elevated side bars 2 of the frame. This supports the receptacle at a point above its center of gravity.

25 In order to effect the connection to the tub for oscillating it, I provide the bracket 11 with a downward extension 24 to which the connecting rod 25 is attached. Any suitable means may be provided for actuating the 30 connecting rod, for example an electric motor 26, supported on a horizontal frame bar 27 in the lower part of the frame.

As an accessory to the tub, I provide a 35 wringer 28, and mechanism driven by the motor for driving the wringer or oscillating the tub independently of each other. Furthermore, the mechanism associated with the wringer enables the wringer to be driven in either direction. In order to accomplish 40 these purposes, the connecting rod 25 is connected to a crank 29 on a suitable shaft 30, the ends of which are rotatably mounted in suitable bearings supported on the frame. The shaft 30 carries a gear wheel 35 which 45 is driven continuously by a pinion 34 on a shaft 31 which is driven from a motor 26 by a belt 33 running over a pulley 32 on the shaft 31. The gear wheel 35 is loosely mounted on the crank shaft 30. One face 50 of this gear wheel 35 is in the form of a clutch-member 36 which co-operates with a sliding clutch member 37 which is mounted on a feather or spline 38 on the shaft 30, so that when it is rotated, it will rotate the 55 shaft. In Fig. 2 this clutch is shown in its open position. On its opposite side the gear wheel 35 is formed into a bevel gear 39 meshing with a bevel pinion 40 attached to the lower end of an upwardly extending 60 shaft 41 for driving the wringer 38.

With the upper end of this shaft 41 is associated a two-way clutch 42, in one position of which the wringer will be driven in one direction, and in the other position 65 of which the wringer will be driven in the

opposite direction. For this purpose, adjacent to the wringer I provide a special frame 43, see Fig. 1, which carries a large bevel gear 44, the shaft 45 of which extends into the wringer and drives the lower roller 46. The upper roller 47 of the wringer is driven by suitable gears 48, from the shaft 45. This gear 44 meshes with two driving pinions 49 and 50, the former engaging its lower ledge while the latter engages its upper ledge. The adjacent faces 51 of these pinions 49 and 50 constitute clutch members, and between them there is mounted a sliding clutch member 52 on the shaft 41, said clutch member being splined in the same 75 manner as the clutch member 37 is splined on its shaft 30. When the clutch member 52 engages the upper end of the lower pinion 49, evidently the wringer will be driven in an opposite direction from the drive that 80 would occur if the clutch member 52 were in engagement with the lower face of the upper pinion 50.

As shown in Fig. 1, this clutch member is in a neutral position, at which time, it 90 engages neither of the pinions 50 nor 51, and hence the wringer will not be driven. The clutch member 52 may be shifted to either of the driving positions described above by means of a suitable lever 53, an arm 54 of 95 which carries a link 55, the lower end of said link being formed into a yoke 56 connecting with the clutch member 52 by means of a loose collar or sliding clutch-member 37.

Adjacent the lever 53, a small quadrant 58 100 is provided, said quadrant having three depressions 59 engaged by a projection on the side of the lever. The lowest of the recesses 59 corresponds to the upper position of the clutch member 52, while the upper depression corresponds to the lower position.

Any suitable means may be provided for opening and closing the clutch, consisting of the clutch members 36 and 37. This is accomplished by a swivel rod 60, the upper 110 end of which is mounted in a suitable bearing 61 attached to a cross bar 62 of the frame. The upper end of this swivel rod carries a suitable lever 63 resting on the cross bar 62. The lower end of the swivel 115 rod 60 is provided with a suitable yoke 64 which engages the clutch member 37 for sliding it in the well known manner.

With this organization of parts, it is evident that when the two-way clutch 42 is in 120 its neutral position, the wringer will not be driven. If the clutch, composed of the members 36 and 37, is closed, the tub will be oscillated. Hence it is evident that the tub and the wringer may be independently 125 driven. It has already been explained how the wringer may be driven in either direction.

I provide means enabling me to utilize the oscillating movement of the receptacle 3 for 130

churning. In order to accomplish this, I prefer to provide a construction such as that illustrated in Fig. 3, in which I provide an inner receptacle 65 which can be suspended

- 5 in the opening 9 after removing the cover 7. When suspended in this way, the inner receptacle 65 extends downwardly into the interior of the tub so that its lower end can dip into a bath of water the level of which 10 may come to about the position of the line *a*, see Fig. 3. In winter time, this water bath will be warm so as to raise the temperature of the cream if it is too cold, and thereby facilitate the bringing of the cream 15 to the proper temperature for churning; likewise, in summer time, if the cream has a tendency to become too warm, the water can be supplied in a cold state. In order to insure that none of the water will splash into 20 the interior of the inner receptacle, the edge of the opening 9 is preferably formed so that it presents a supporting ledge 66, and the upper end of the inner receptacle 65 is formed with a lateral projection or shoulder 25 67 which rests on this ledge so as to support the inner receptacle. Beyond this shoulder 67, the inner receptacle presents an upwardly extending neck 68. In addition to this, the inner receptacle is provided with a removable cover 69 which rests upon the inner side of the shoulder 67.

It is evident that by using such an inner receptacle the oscillation of the tub can be utilized to churn the cream into butter.

- 35 Furthermore, it will be seen that the act of converting the washing machine into a churn is a very simple one.

It is understood that the embodiment of the invention described herein is only one of 40 the many embodiments or forms this invention may take, and I do not wish to be limited in the practice of my invention, nor in my claims to the particular embodiment set forth.

- 45 What I claim and desire to secure by Letters Patent, is:

1. In a machine of the class described, the combination of a frame, an elongated receptacle, a bracket mounted on each side of 50 said receptacle, securing means engaging the edges of each side toward each end, for clamping each bracket in position, said brackets having trunnions supported on said frame to enable the receptacle to swing on said frame, and means attached to one of said brackets for oscillating said receptacle.

2. In a machine of the class described, the combination of a frame, an elongated receptacle, a bracket disposed on each side of 55 said receptacle engaging the bottom edge of each side, securing means attached to each

bracket extending upwardly and engaging the upper edge of the side of the receptacle toward each end, for clamping each bracket to the receptacle, said brackets having trunnions supported on said frame to enable the receptacle to swing on said frame, and means attached to one of said brackets for oscillating said receptacle.

3. In a machine of the class described, the 65 combination of a frame, an elongated receptacle having sides with projecting edges on opposite sides of the vertical middle axis of each side, a bracket disposed on each side of said receptacle engaging the bottom, securing means including saddles mounted on said projecting edges on each side and at each end of the receptacle, said securing means being connected with said brackets to hold said brackets in position, said brackets 70 having trunnions supported on said frame to enable the receptacle to swing on said frame, and means attached to said brackets for oscillating said receptacle.

4. In a machine of the class described, the 75 combination of a frame, an elongated receptacle having sides with a projecting bead adjacent the bottom of said receptacle and having upper projecting beads on opposite sides of the vertical middle axis of each side, a bracket disposed on each side of said receptacle engaging the bottom bead at each side, securing means including saddles mounted on each of said upper projecting beads, on each side and at each end of the 80 receptacle, said securing means being connected with said brackets to hold said brackets in position, said brackets having trunnions supported on said frame to enable the receptacle to swing on said frame, and means attached to said brackets for oscillating said receptacle.

5. In a machine of the class described, the 85 combination of a frame, an elongated receptacle having a bottom and having sides 90 with elevated corners, a bracket disposed on each side of said receptacle engaging the bottom, saddles seating on the upper corners of each side, an inclined stem connected at its upper ends to each saddle, and secured to 95 the bracket at its other end, said stems affording means for clamping the brackets to the sides of the receptacle, said brackets each having a trunnion for rotatably supporting the receptacle on said frame, and means connecting with the lower portion of one of said brackets for oscillating the receptacle.

In testimony whereof, I have hereunto set my hand.

WILLIAM H. SARGENT,
